UNITED STATES PATENT OFFICE

130,233

DESIGN FOR A SHOE SOLE

Arthur E. Pfeiffer, Worcester, Mass.

Application September 17, 1941, Serial No. 103,392

Term of patent 3½ years

To all whom it may concern:

Be it known that I, Arthur E. Pfeiffer, a citizen of the United States and a resident of Worcester, in the county of Worcester and Commonwealth of Massachusetts, have invented a new, original, and ornamental Design for a Shoe Sole, of which the following is a specification, reference being had to the accompanying drawing, forming a part thereof, in which

Fig. 1 is a view in side elevation of a shoe sole showing my new design,

Fig. 2 is a view in perspective showing the upper surface of the sole, and

Fig. 3 is a view in perspective showing the bottom or tread surface of the sole.

I claim:

The ornamental design for a shoe sole, substantially as shown and described.

ARTHUR E. PFEIFFER.
